MEMORANDUM PAD HOLDER

Warren A. Dillen, Jeffersontown, Ky., assignor to Reynolds Metals Company, Richmond, Va., a corporation of Delaware

Application October 31, 1956, Serial No. 43,609

Term of patent 14 years

(Cl. D74—1)

The figure of the drawing is a front perspective view of a memorandum pad holder, showing my new design. The rear undisclosed side is similarly ornamented and presents a similar appearance as the side shown.

The dot and dash line illustration of a memorandum pad is for illustrative purposes only.

I claim:

The ornamental design for a memorandum pad holder, substantially as shown and described.
